UNITED STATES PATENT OFFICE

RUDOLPH J. ANSCHICKS, OF CHICAGO, ILLINOIS, ASSIGNOR TO PROTECTOSEAL COMPANY OF AMERICA, OF CHICAGO, ILLINOIS, A CORPORATION OF ILLINOIS

LIQUID-LEVEL INDICATOR

Application filed October 23, 1924. Serial No. 745,429.

My invention belongs to that general class of devices known as gauges or indicators and relates particularly to a gauge adapted to be used in connection with liquid containers provided with a filler opening such as gasoline or like tanks, containers, cans, etc.

The device is particularly designed to be applied to the tank at the filler opening and is also applicable to tanks provided with filler or safety tubes projecting into the tank. In the embodiment of the invention shown the same is combined with a safety tube which is insertable in the tank or receptacle through the filler opening. Generally speaking it may be said that safety tubes are used on tanks or receptacles at the filler opening for preventing excessive pressure being generated in the tank, or to prevent the contents of the tank from exploding or the escape of liquid from evaporation as well as to facilitate the filling or emptying of the tank or can. The device illustrated is particularly designed for receptacles containing explosive contents. The invention has among its other objects the production of a device of the kind described, which is simple, convenient, compact, durable, efficient and satisfactory for use wherever found applicable. Many other objects and advantages of the construction herein shown and described will be obvious to those skilled in the art from the disclosures herein given. To this end my invention consists in the novel construction, arrangement and combination of parts herein shown and described, and more particularly pointed out in the claims.

In the drawings, wherein like reference characters indicate like or corresponding parts:

Fig. 1 is a sectional view of a portion of a tank with safety tube applied thereto;

Fig. 2 is a sectional view taken substantially on the line 2—2 of Fig. 1;

Fig. 3 is a sectional view taken substantially on the line 3—3 of Fig. 1;

Fig. 4 is substantially a sectional view taken on the arc 4—4 of Fig. 2 showing the inner tube in elevation;

Fig. 5 is an enlarged view of one of the indicators;

Fig. 6 is a view in elevation of a modified gauge construction;

Fig. 7 is a sectional view taken substantially on line 7—7 of Fig. 6;

Fig. 8 is a sectional view taken substantially on line 8—8 of Fig. 6;

Fig. 9 is a view in elevation of another type of mechanism; and

Fig. 10 is a sectional view taken substantially on line 10—10 of Fig. 9.

Referring to the drawings in which the preferred embodiments of the invention are shown, it may be mentioned that 1 represents a tank or receptacle of suitable size, shape and material provided with a filler or vent opening 2 at which is generally arranged a flange 3. Suitably mounted on the flange 3, as shown in threaded engagement therewith, is a closure member 4 which has an opening therethrough and carries a pair of concentric radially faced tubes 5 and 6 of suitable size, shape and material. I have illustrated tubes made up of perforated sheet metal, it being understood that either one or both may be made of the perforated metal, wire gauze or the equivalent. Generally, I prefer the perforated metal. The lower ends of these tubes are shown closed by bottoms 7 and 8, respectively. The two tubes are secured to the closure member 4 in any suitable manner, preferably, as indicated, or in an equivalent manner, and I prefer to provide a plurality of openings 9 through the closure member about the central opening and at the outer side of the inner tube, as shown. These openings are of the desired size and number and arranged generally about or around the opening (see Fig. 2) and prevent the contents of air locking in the receptacle.

The central opening and openings 9 are normally closed by a cover or cap member 10, which may be flanged at the edge, as indicated at 11, and arranged to closely fit the shoulder 12 on the member 4. The cap member or cover 10 is shown pivotally connected at 14 to an arm 13, which is hinged to the member 4, as indicated at 15 or in an equivalent manner, a spring 10^a being provided to hold the cap member in its closed position. I have not considered it necessary to illus-

trate in details the cover construction or the method of attaching the same to the member 4, as obviously other forms of securing the cover in place may be employed. The particular cover shown is itself provided with a valve device 10^b which is preferably substantially like that shown in U. S. Letters Patent, 1,457,976.

Only one embodiment of my invention is shown herein to illustrate the application of the gauge to an opening, either the filler opening or a vent opening, as well as a possible construction with a safety tube. One of the tubes, as shown inner tube 6, is constructed as indicated at 18 with an offset side wall providing a float chamber, which is shown divided by partitions 19 forming a plurality of associated float chambers 20. There is thus formed substantially a tube or well within which float mechanism may be arranged. Arranged within each float chamber is a float, indicated at 21, 22, 23 and 24, four floats and float chambers being shown. Extending from each float, which may be of cork, or any other construction suitable for the purpose, is a member or rod 25 extending to the upper or open end of the tubes. As shown, these members project up into or to the openings 9 and if desired they may be each provided with heads 26. I have illustrated in Fig. 5 how the heads 26 may be recessed and the recesses filled in by enamel 27 or the like. These heads may bear certain symbols such as 1/4, 1/2, etc., or letters, or the like, indicating which float they are connected with, and consequently the quantity of liquid in the tank. However, it is generally preferred to place the symbols on the top of the member 4 adjacent the heads, as indicated at 28 in Fig. 2. While only one float and indicator may be employed, as for example, one to indicate that the tank is empty or the contents getting low, it is generally preferred to provide the plurality of indicators so that the user may be able to ascertain from time to time the level in the tank and thereby be fully advised at all times. I have shown guides 29 at either side of the chambers arranged to coact with the slides 30 on the floats and guide the same in their travel and prevent binding of the parts.

The operation of the device illustrated may briefly be described as follows: When the floats are all down, as shown in the full lines in Fig. 4, it indicates that the tank is empty or practically so. I have illustrated as an example in Fig. 4, in dotted lines, the operation of the gauge when there is some liquid in the tank, the floats 21 and 22 here indicating at the filler opening that there is at least some liquid in the tank, the amount being indicated at the top. The indicators 26 at the top and the top cover may be so designed that the indicators are substantially out of sight when the floats are down but dis-

played substantially flush with or above the portion 4 when the floats are raised. While ordinarily they do not engage the cover even when up, of course, this is a matter of proportioning the parts as they may be designed to engage with the underside of the cover when closed and be maintained down by the cover but flip up when the cover is open. Generally speaking, however, they do not project up to any extent so that they are not easily injured during the filling of the tank by the funnel or supply hose connection or nozzle. By providing a plurality of floats arranged in separate compartments they have a limited movement within the limits of the compartments so that there is only a limited movement at the indicators and the extent of movement may of course be varied by varying the proportion of the parts. As shown, the connecting rods 25 are so formed that in engaging the tops of the float compartments they serve as stops.

Referring to Figs. 6, 7 and 8, I have shown a tube 31 provided with the part 32 flanged as at 33 and 34 to form the float chambers and guides, the part being secured to the inner tube as indicated at 35 or in any equivalent manner. In this case (see Fig. 7) float 36 is provided with a bar 37, formed with the notches 38 for engagement with the guides 34. Obviously, any equivalent guide construction and engaging means may be employed. Extending from the float is an arm 39, which is connected to one of the rods, as shown, rod 40, which extends to the top of the tube. Float 41 is connected with rod 42, float 43 with rod 44, and float 45 with the rod 46, etc. These rods are shown guided by the plates 47 and 48. I also have shown a shelf or bracket 49 arranged to receive and support the lower ends of the float rods, when in down position, which rods may be formed with heads 50.

In the construction shown in Figs. 9 and 10, a modified arrangement of rods is employed. Referring to these figures, 51 represents the tube and 53, 54, 55 and 56 floats which are arranged in the float container 52 and guided as in the construction previously described, or in a similar manner. The several rods 57 extend to their respective floats and may be secured thereto in any suitable manner, the one shown (see Fig. 10) being bent up as at 58 to interengage with the float. In this form, there are provided the partitions 59, 60, 61 and 62, which confine the floats and limit their movements.

It will be noted that with any of the constructions described, so far as the gauge mechanism is concerned, the outer tube 6 is not essential, and if the float container 18, 32 or 52, as the case may be, is secured to the outer tube, the inner tube may be omitted without affecting the float mechanism.

It will be noted that the application of the

gauge or combination of the same with the tube does not in any way interfere with the filling of the receptacle nor does it in any way affect the functions of the tube. The application of a gauge in this manner also makes possible the application of a gauge to a smaller portable receptacle, such as safety cans containing a gallon or five gallons, or whatever size it may be. The same is so simple and inexpensive that it may be applied to such smaller receptacles at a very low cost. The device also has the advantage that it brings the filler opening and the gauge together, which adds to the convenience and there is required but one opening in the tank for the gauge or combined gauge and filler tube. In some instances the mechanism, instead of being applied at the filler opening, is applied at the vent openings or pipes, which are provided on large storage tanks and where the filling is generally from the bottom of the tanks.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. The combination with a tank having a filling opening, of a plurality of spaced concentric foraminous tubes projecting downward from said filling opening, means carried by said tank at said filling opening to carry said tubes, said means being provided with a plurality of apertures between the walls of said tubes whereby air may escape from the space therebetween, a float disposed in said space, a rod carried by said float and arranged to move up and down through one of said apertures, and a pivoted cap for closing said filling opening and said apertures, said cap being adapted to hold said float and rod functionally inoperative when in closed position.

2. The combination with a tank having a filling opening, of a plurality of concentric foraminous tubes projecting downward from said filling opening, means carried by said tank and said filling opening to carry said tubes, said means being provided with a plurality of apertures between the walls of said tubes whereby air may escape from the space between the tubes, a plurality of floats in said space, an indicating member carried by each float, said indicating members being of different lengths and each of them being arranged to pass up and down through one of said apertures, and a pivoted cap for closing said filling opening and said apertures.

3. In a device of the kind described and in combination, a closure member arranged for securedment to a tank and provided with an

opening, a pivoted cover carried by said member and arranged to normally close said opening, a plurality of tubes arranged one within the other and carried by said closure member at the under side thereof, said tubes being constructed and arranged to provide a float chamber therebetween, a float arranged in said chamber and provided with means extending to the top of said closure member below said cover and having an indicator, said pivoted cover when in closed position being adapted to hold said float and said means in a functionally inoperative position, and means for limiting the upward movement of said float.

4. In a device of the kind described and in combination, a pair of spaced perforated tubes arranged one within the other, the inner tube being indented to provide a chamber at one side thereof between the tubes, transverse partitions arranged in said chamber dividing the same into a plurality of compartments, float members arranged in said compartments, and means operatively connected to said floats and projecting through to the upper ends of the tubes for indicating movement of the floats, and a cover normally covering the upper ends of said tubes and said indicating means.

5. In a receptacle having a filling opening therein, a tubular foraminous member secured at said opening and projecting into said receptacle, a movably mounted cap for closing said filling opening, liquid level indicating means including a float disposed in said foraminous member, said indicating means being functionally inoperative when the cap is closed, and means disposed within said foraminous member for protecting the float when liquid is poured into the receptacle.

In testimony whereof, I have hereunto signed my name.

RUDOLPH J. ANSCHICKS.
